RAG DOLL

Cecelia Jeannette Cummings, 3033 S. D St.,
Oxnard, Calif. 93030

Filed May 26, 1969, Ser. No. 17,352

Term of patent 14 years

Int. Cl. D21—02

U.S. Cl. D34—4

FIG. 1 is a perspective view of a rag doll showing my new design;

FIG. 2 is top plan view thereof;

FIG. 3 is a side elevational view thereof, showing the side not shown in FIG. 1;

FIG. 4 is a front elevational view thereof; and,

FIG. 5 is a rear elevational view thereof.

I claim:

The ornamental design for a rag doll, substantially as shown.
